(57) **CLAIM**

The ornamental design for a two-point discriminator sensory measurement device, as shown and described.

DESCRIPTION

FIG. 1 is a front right perspective view of a first embodiment of the design;

FIG. 2 is a front side elevational view thereof;

FIG. 3 is a back side elevational view thereof;

FIG. 4 is a left side elevational view thereof;

FIG. 5 is a right side elevation view thereof;

FIG. 6 is a top plan view thereof; and,

FIG. 7 is a bottom plan view thereof.
